UNITED STATES PATENT OFFICE.

LEWIS EDWIN PEASE, OF ABINGTON, MASSACHUSETTS.

LIFE-SAVING APPARATUS.

SPECIFICATION forming part of Letters Patent No. 518,857, dated April 24, 1894.

Application filed July 10, 1893. Serial No. 480,042. (No model.)

To all whom it may concern:

Be it known that I, LEWIS EDWIN PEASE, a citizen of the United States, residing at Abington, in the county of Plymouth and 5 State of Massachusetts, have invented a new and useful Life-Saving Apparatus, of which the following is a specification.

My invention relates to life saving apparatus especially designed for use by firemen, 10 and it has for its object, an apparatus so constructed and arranged as to fill, what has long been a desideratum with firemen, namely:—a rope constantly on hand in case of need, yet in no way impeding free action.

15 Figure 1 represents in elevation an inside view of a fireman's coat provided with a coil of rope, the lining or straps used to secure the rope to the coat being removed in order to show the rope more clearly. Fig. 2 is a

20 sectional view of Fig. 1 on the line A B showing in section the coat, rope, and rope retaining lining or strap. Fig. 3 represents in elevation one side of the coil of rope and rope retaining strap. Fig. 4 is an enlarged view

25 of the friction stop or guard shown in Fig. 1 and a portion of the rope. Fig. 5 represents upon an enlarged scale in side elevation a piece of the rope provided with a guard stop formed out of the rope, and Fig. 6 is a front 30 elevation of Fig. 5.

The fireman's garment or coat 10, the inside of which is shown in Fig. 1, is of the ordinary material and of the usual style, and it is provided with the coil of rope 11 which 35 is secured to the coat by means of the strap

12 as shown by Figs. 2 and 3 or by means of a lining, in such a manner, as to permit the coiled rope to be readily detached from the coat in case of need. One end of the rope 40

which may be provided with the eye or ring 13 which may be used to form a noose to facilitate, in case of necessity, the fastening of the rope. The rope is also provided with friction stops or guards 14 one of which is represented by Figs. 1 and 4 to make the descent of a person using the rope easier, or 45 more effective, and for the same reason, if desired, the rope may be provided with the fixed stops or guards, as 15, one of which is

50 shown in Figs. 5 and 6. A coil of rope one half inch in diameter applied to a coat as represented by Fig. 1 would be about one

hundred and thirty feet long and would weigh about nine pounds. It will be observed that this weight, which is trifling, is borne 55 mainly from the shoulders of the wearer and that in removing the rope the lining or straps only (not the coat) would be injured.

In the use of my life saving apparatus the hands of the wearer will be free and the coil 60 of rope will always be at hand to be used to lower one's self and others and to throw to people who might otherwise jump to the ground.

It is designed that the coil of rope may be 65 easily detached, commencing either at the top or bottom of the coil without even removing the coat. The stop guards may be used to make the descent of the user safe, unaccompanied by injurious results, especially 70 to the hands.

The rope may be treated with any well known solution to render it fire proof.

For the purpose of permitting the easy bending of the coat when in use, the rope 75 coils are placed in horizontal courses; but for some special uses it may be desirable to place the rope coils in vertical courses.

What I claim as new, and desire to secure by Letters Patent, is—

80

1. A life saving apparatus consisting of a fireman's coat provided with a coil of rope which is secured to the coat by means of a lining or straps, as shown and described, so that the rope can be readily separated from 85 the coat, in case of need, substantially as described.

2. A fireman's coat provided with a detachable coil of rope secured to the inner back portion of the coat, said rope being provided with the stop guards, substantially as 90 described.

3. In a life saving apparatus, the combination of a fireman's coat and a coil of rope secured in a detachable manner thereto, said 95 coils being disposed in horizontal courses, substantially as described.

In testimony whereof I have signed my name to this specification in the presence of two subscribing witnesses.

LEWIS EDWIN PEASE.
